PAGE 3

Fig. 4

Fig. 5

Fig. 6

Fig. 7

FIGURE 1 is a perspective view of a baby carrier showing my new design;

FIGURE 2 is a side elevational view of the same;

FIGURE 3 is a longitudinal sectional elevation of the same;

FIGURE 4 is a top plan view thereof;

FIGURE 5 is a transverse sectional elevational view taken substantially on line 5—5 of FIGURE 2;

FIG. 6 is a front elevational view of the baby carrier; and

FIG. 7 is a rear elevational view thereof.

I claim:

The ornamental design for a baby carrier, as shown.
